LADY'S GARMENT

Maud L. Rieffannacht, New York, N. Y.

Application January 16, 1931. Serial No. 509,079

5 Claims. (Cl. 2—83)

This invention relates to garments of the one-piece variety having a body portion and integral or attached leg portions, and more specifically to a concealed utility seat for such garments.

5 One object of my invention is to provide a utility seat for one-piece garments such as pajamas, which may be particularly adapted either for evening wear or for sleeping purposes, for sport wear as at summer beach resorts, or for ordinary 10 wear about the house; or for bathing suits of knitted or other fabric; or in fact for any one-piece lady's garment other than under-garments having integral body and leg portions.

Wearers of garments of the kind to which the 15 present novel utility seat is adapted to be applied have heretofore been under the necessity of practically disrobing for utility purposes, and the advantages of the new and improved utility seat embodied in my invention will be obvious. With 20 the improved construction which I provide, a utility seat which is normally perfectly concealed offers immediate and ample accessibility and convenience for utility purposes without the necessity of disrobing, or even of disturbing those fastenings or parts of the garment which are ordinarily used in connection with donning or doffing 25 the same.

With these and other objects in view the invention consists in the novel construction and arrangement of parts hereinafter described, illustrated in the accompanying drawing, and particularly pointed out in the appended claims, it being understood that various changes in the form and construction may be made without departing from 35 the spirit of the invention or sacrificing any of the advantages thereof.

In the drawing:

Figure 1 is a back view in perspective of a garment embodying my invention, shown opened at 40 one side of the seat, and showing in dotted lines the construction of the other side of the seat which is closed.

Fig. 2 is a side view of the garment shown in Fig. 1; and

45 Fig. 3 is a partial back view of a modified form of the seat and garment shown in Fig. 1.

Referring particularly to Figs. 1 and 2, I have here shown lady's pajama suit of the one-piece, sun-back type adapted for evening wear or similar use, which consists of a body portion 1 and integral leg portions 2. This pajama suit is completely closed in front, is fitted to the waist and has flexible stiffening members 3 enclosed in the side seams. It is made full at the rear by means 55 of two box pleats 4, one fold 5 of each pleat be-

ing concealed in the leg portions 2 and the other folds 6 of the box pleats meeting at the back central seam of the garment seat. The folds 5 of the box pleats are shown slit downwardly on lines 60 slightly converging toward the crotch, and the upper edges of the two outer thicknesses of the box pleats are sewn together along the line and as indicated at 7. Means, such as snap fasteners 8 are provided on each side of the slit folds 5 for fastening the garment, and means, such as the 65 loops 9 are provided at the top on the closed center folds 6, such loops 9 of each fold to engage common buttons 10 on the underneath third thickness of material which forms the back of the garment at the waist line. By thus slitting the 70 two folds 5 at each side as will be seen a free upwardly extending tongue portion 11 is left which is entirely concealed by the box pleats 4 and to which the said pleats are fastened when the garment is normally adjusted on the wearer, but 75 which, for utility purposes may be conveniently unfastened by means of the snap fasteners 8 and loops and buttons 9, as well as for donning and doffing the pajamas. In the modified form shown in Fig. 3 one of the folds 5 is left unslit as at 80 12 and accessibility for utility purposes is had in this case through merely the one slit-fold 13.

Although the drawing and the above specification disclose the best modes in which I have contemplated embodying my invention, I desire to 85 be in no way limited to the details of such disclosure, for in the further practical application of my invention, many changes in the construction and in the details may be made as circumstances may require or experience suggest without departing from the spirit of the invention 90 within the scope of the appended claims.

What I claim and desire to secure by United States Letters Patent is:

1. In a garment of the class described, a utility 95 seat portion comprising an interior downwardly tapered tongue extending into the crotch of the garment, separable outer parts loosely covering said tongue and meeting at the vertical center line in the form of loosely hanging pleats, and 100 means detachably supporting the upper part of said tongue in close contact with the body.

2. In a garment of the class described, a utility seat, comprising a downwardly tapering integral tongue portion, fastening means on the garment 105 and on said tongue portion for securing the tongue portion tightly against the body, and relatively loose means in the form of loosely hanging pleats for concealing said tongue.

3. In a garment of the class described, a utility 110

seat, comprising a downwardly tapering integral tongue portion, fastening means on the garment and on said tongue portion for securing the same in close contact with the body, outer separable 5 relatively loose means in the form of loosely hanging pleats for concealing said tongue, and fastening means for securing said concealing means.

4. In a garment of the class described, a utility seat comprising two adjacent vertical pleats, an 10 upwardly extending tongue, fastening means on

the garment and on said tongue for securing the latter, and means for fastening said pleats so as to conceal said tongue.

5. In a garment of the class described, a utility seat comprising pleats with abutting edges, an 80 upwardly extending independent tongue, fastening means on the garment and on said tongue for securing the latter, and means for fastening said pleats to conceal said tongue.
